UNITED STATES PATENT OFFICE.

EDWIN NORTON, DECEASED, BY LUCY E. NORTON, EXECUTRIX, OF NEW YORK, N. Y.,
ASSIGNOR TO PERFECT VACUUM CANNING COMPANY, OF NEW YORK, N. Y., A COR-
PORATION OF MAINE.

JAR-CLOSURE.

1,308,606.

Specification of Letters-Patent.

Patented July 1, 1919.

Application filed June 4, 1915. Serial No. 32,199.

To all whom it may concern:

Be it known that I, LUCY E. NORTON, a citizen of the United States, and a resident of New York city, county of New York, and 5 State of New York, executrix of the last will and testament of EDWIN NORTON, deceased, (as by reference to the duly-certified letters testamentary hereto attached will more fully appear,) am in possession of new and useful 10 Improvements in Jar-Closures, of which the said EDWIN NORTON was the inventor, and of which the following is a specification.

The invention relates to new and useful improvements in jar closures and more particularly to a jar closure wherein the cover is clamped to the mouth of the jar by a clamping ring.

An object of the invention is to provide a jar closure wherein a clamping ring may be 20 used to temporarily hold the parts in assembled position and wherein said clamping ring may be operated upon by suitable tools for sealing the closure to the jar.

In the drawings which show by way of 25 illustration one embodiment of the invention:

Figure 1 is a vertical sectional view showing the improved jar closure with the parts separated;

30 Fig. 2 is a vertical sectional view showing the parts assembled on a jar and the securing ring curled to seal the closure to the jar.

The invention consists generally in providing a jar having a flange or lip to which a 35 split ring is adapted to be attached, said ring having an inturned part adapted to extend underneath the flange. Directly on top of the mouth of the jar is a paper lining and on top of this paper lining is a metal cap 40 having a downwardly projecting flange adapted to be provided with a sealing material which is forced against the tapered outer wall of the mouth of the jar. Outside of this metal cap is the clamping ring and 45 after the parts have been assembled the outer edge of the clamping ring is curled in order to force the metal cap into contact with the jar and the tapered wall with the sealing material thereon, against the side 50 wall of the jar.

Referring more in detail to the drawings:

The jar is shown at 1 and this jar has a wide open mouth 2. At the outer wall of the mouth of the jar is a projecting flange 3 hav-

ing a shoulder 4. The jar mouth is closed 55 first by a lining 5 which is practically in the form of a paper disk and this paper disk may be treated in order to make the same water proof if desired. Above the paper disk 5 is a metal cap 6 which is closed at its 60 upper end as at 7 and is provided with a downwardly projecting cone shaped flange 8. The inner wall of this flange is coated with a plastic sealing material as at 9. The outer wall of the jar is tapered as at 10 to 65 conform to the tapered wall 9 of the metal cap 6. The metal cap and paper lining are held to the jar by a clamping ring 11 which as herein shown is a split ring having a tongue 12 adapted to extend through a slot 13 and 70 the tongue is bent back as indicated in dotted lines in Fig. 1 to lock the split sections of the ring together. This ring is tapered to conform in a general way to the tapered wall of the metal cap 6. At the lower edge 75 of the ring there is an inwardly projecting flange 14 while at the upper edge of the ring there is a vertical portion 15.

In the applying of the closure to the jar the paper disk or lining 5 is first placed on 80 the mouth of the jar after which the metal cap 6 is laid over the lining. The split ring 11 with its sections separated is then placed on the jar and the tongue 12 is bent back in order to lock the split sections together. 85 When the ring is placed on the jar the inwardly turned part 14 of the ring extends underneath the shoulder 4 at the mouth of the jar. After the parts have been thus assembled the jar may be placed in a vacuum 90 chamber and the metal cap and lining and ring will rest so lightly on the mouth of the jar that the air can be withdrawn from the jar and the contents placed under vacuum. While the jar is still in the vacuum 95 chamber a suitable curling head may be applied to the flange 15 of the securing ring 11 so as to roll or curl the flange as indicated at 16 in Fig. 2. This rolling of the flange down onto the upper flat ledge 17 of the cap 6 will press the cap firmly down onto the mouth of the jar. The inwardly projecting portion 14 holds the ring so that the rolling of the curl will cause this clamping action.

100 The cap is preferably so proportioned that when it is crowded onto the mouth of the jar the sealing material indicated at 9 will

be forced against the outer wall of the jar and form a tight joint. This effects a sealing of the jar so that the vacuum in the chamber may be released.

5 The curling of the vertical wall may be accomplished by any suitable curling head such as a rotating head having a curling roll or a head having a die for simultaneously curling the entire vertical wall at the same 10 time.

It will be readily seen that the closure may quickly be removed by piercing the tin cap to break the vacuum in the jar, and releasing the split ring through the turning 15 of the tongue 12 so as to release the split sections. The above closure, therefore, has the advantage that the parts may be assembled on the jar and held in the assembled position during the handling of the same.

20 The contents of the jar may be placed under vacuum and then the closure operated upon to form a perfect seal which will hold said jar under vacuum. The closure may be quickly released by hand and without the 25 use of tools merely by separating the split sections of the retaining ring, then piercing the cap.

It is obvious that minor changes in the details of construction may be made without

departing from the spirit of the invention 30 as set forth in the appended claim.

Having thus described my invention what I claim as new and desire to secure by Letters Patent is:—

The combination with a jar having an 35 outwardly extending flange provided with a tapered outer wall and a beading at its upper end, of a metal cap having an annular groove receiving the beading and a down- 40 wardly extending flange engaging the tapered wall of the flange, a paper lining between the metal cap and upper edge of the jar, and a split metal retaining ring having an inturned portion at its lower edge adapted to engage underneath the flange, said 45 ring having a flange at its upper edge adapted to be rolled so as to clamp the cap against the jar and press the paper lining tight down upon the upper end of the jar.

In testimony whereof I affix my signature 50 in the presence of two witnesses.

LUCY E. NORTON,
*Executrix of the estate of Edwin Norton,
deceased.*
